UNITED STATES PATENT OFFICE.

JOSEPH S. WILCOX, JR., OF ATHOL, AND ALBERT TURNER AND HOWARD W. DUNBAR, OF WORCESTER, MASSACHUSETTS, ASSIGNEES TO NORTON GRINDING COMPANY, OF WORCESTER, MASSACHUSETTS, A CORPORATION OF MASSACHUSETTS.

FEEDING DEVICE FOR GRINDING-MACHINES.

1,197,700.

Specification of Letters Patent. Patented Sept. 12, 1916.

Application filed June 28, 1915. Serial No. 36,780.

To all whom it may concern:

Be it known that we, JOSEPH S. WILCOX, Jr., ALBERT TURNER, and HOWARD W. DUNBAR, citizens of the United States, said WILCOX residing at Athol, in the county of Worcester and State of Massachusetts, said TURNER and DUNBAR residing at Worcester, county of Worcester, and State of Massachusetts, have invented a new and useful 10 Feeding Device for Grinding-Machines, of which the following is a specification.

This invention relates to an improved ratchet feeding device capable of general application but more particularly designed 15 for automatically actuating the transverse wheel feed of a grinding machine.

The invention is herein disclosed as applied to a grinding machine of the type described in the patent to Norton No. 762,838, 20 issued Jan. 14, 1904 and further described in the patent to Spence, No. 1,121,773, issued Dec. 22, 1914. The machine shown in these prior patents is provided with an automatic cross feed actuated by a reversing lever operated by adjustable dogs carried by the longitudinally movable work carriage. As the carriage approaches the end of its travel in either direction the lever is reversed by one of the dogs and each movement of the lever 25 30 in either direction operates the cross feed to move the grinding wheel toward the work.

It is the general object of our invention to improve the ratchet feeding devices through which the reversing lever is connected to move the grinding wheel transversely.

In the previous commercial form, as more clearly shown in the patent to Spence, a ratchet wheel was provided which was actuated by a feed pawl which continually engaged the ratchet wheel during both its operative and inoperative movements. Such engagement of the feed pawl with the wheel during the idle or backward stroke caused 40 45 the pawl to drag over the teeth of the wheel, thereby causing excessive and useless wear of the teeth and pawl.

Accordingly one of the principal features of our invention relates to the provision of 50 means for causing the feed pawl to perform its idle or backward stroke out of contact with the ratchet wheel.

Other features of our invention relate to

certain devices, arrangements and combinations of parts which will be hereinafter described and more particularly pointed out in the appended claims.

A preferred form of our invention is shown in the drawings in which—

Figure 1 is a front elevation of a grinding machine with our improved feeding device mounted thereon; Fig. 2 is an enlarged sectional view taken substantially along the axes of the cross feed screw and the ratchet wheel; Fig. 3 is an enlarged front elevation 65 of the ratchet feeding mechanism; Fig. 4 is a side elevation of the feed pawl; Fig. 5 is a front elevation of certain of the parts shown in Fig. 3, the parts being shown in a different position, and Fig. 6 is a plan view 70 of the hand feeding device taken in the direction of the arrow 6 in Fig. 3, certain parts being shown in section.

Referring to Fig. 1, our invention is shown in connection with a machine in which the work carriage 10 is longitudinally movable and has mounted thereon adjustable dogs 11 and 12. As the carriage 10 approaches the end of its travel in either direction one of the dogs 11 or 12 contacts with a reversing lever 13 mounted to turn about a pivot 14. A curved arm 15 is rigidly secured to the lever 13 and is movable therewith. A sleeve 16 is adjustably mounted upon the arm 15 and a rack 17 is pivotally connected to an extension of the sleeve 16. The rack 17 engages a pinion 18 pivoted upon a stud 19 and secured to a disk 20 provided with a crank pin 21. The parts are so proportioned that the angular movement imparted to the reversing lever 13 by the dogs 11 or 12 will move the rack 17 in one direction or the other a distance sufficient to partially rotate the pinion 18 and the crank pin disk 20 connected thereto. 95 The extent of this partial rotation may be regulated by adjusting the sleeve 16 along the curved arm 15 toward or away from the pivot 14. The ratchet wheel 22 is loosely mounted upon a fixed stud 23 (Fig. 2) and has fixed thereto a pinion 24 meshing with a gear 25 mounted on the cross feed screw 26. The screw 26 engages a threaded nut 27 mounted below the grinding wheel carriage 28. The parts thus far described form no 105 part of our present invention and a more

complete disclosure thereof may be found in the patents to Norton and Spence previously mentioned.

Our invention relates more particularly to the feeding devices through which angular movement of the crank pin 21 is rendered effective to rotate the ratchet wheel 22 and these devices will now be described.

Referring particularly to Figs. 3, 4 and 5 we provide a supporting arm 29 loosely mounted upon a sleeve 30 fixed to the frame of the machine and concentric with the ratchet wheel 22. In order to provide a certain resistance to the angular movement of the arm 29, a friction disk or spring washer 31 (Fig. 6) is provided which engages one side of the hub of the arm 29 and forces the hub against a shoulder 32 on the fixed sleeve 30. A nut 33 is threaded on the sleeve and constitutes means for forcing the friction disk 31 against the hub of the arm 29 with the necessary friction pressure. A feed pawl 34 (Fig. 3) is pivotally mounted upon a stud 35 on the outer end of the supporting arm 29 and is connected by a link 36 to the crank pin 21. A tooth 37 of hardened steel or other durable material is provided near the outer end of the feed pawl 34 for engagement with the ratchet wheel 22. The stud 35 in the end of the supporting arm 29 provides a support for an angularly adjustable cam 38 having oppositely disposed inclined faces as clearly shown in Figs. 3 and 5. A plunger 39 is mounted to slide longitudinally in a recess formed in the feed pawl 34, said plunger being provided with suitable cam-engaging surfaces at its lower end. Rotation of the plunger is prevented by a screw key 40 (Fig. 3) projecting into a key-way 41 formed in one side of the plunger and a spring 42 mounted in the recess in the arm 34 forces the plunger 39 into yielding engagement with the cam 38.

The normal position of the parts is shown in Fig. 5, the tooth 37 being out of engagement with the ratchet wheel 22 and the plunger 39 engaging the right hand surface of the cam 38. With the parts in this position the movement of the work carriage 10 will be toward the right until the dog 11 engages the reversing lever 13, such engagement causing a movement of the rack 17 toward the left as viewed in Fig. 3. This movement of the rack 17 will move the crank pin 21 in a circular path from the position shown in Fig. 5 to the dotted line position 21^a in the same figure. This movement of the crank pin causes a movement of the link 36 downward followed by a corresponding upward movement. As the link moves downward the friction pressure upon the arm 29 retards the movement of the arm and the feed pawl 34 swings freely about its pivot 35 until it engages the ratchet wheel 22, by which engagement further swinging

movement of the feed pawl is prevented. The link 36 will thereafter move the supporting arm 29 and the feed pawl 34 as a unit about the center of the stud 23, thus advancing the ratchet wheel a predetermined amount. As the crank pin 21 passes its lower center the link 36 will begin to move upwardly, upward movement of the arm 29 is resisted by the friction of the disk 31 and the feed pawl 34 swings upon its stud 35 away from the ratchet wheel until the plunger 39 engages the cam 38. Further rotation of the feed pawl 34 upon the stud 35 is yieldingly resisted by the engagement of the plunger with the cam. The supporting arm 29 thereafter moves about its pivot 30, thereby returning the feed pawl 34 and its tooth 37 to their original positions. The tooth 37 thus describes a substantially rectangular path as indicated in dotted lines in Fig. 5, the operative feeding stroke only being performed with the tooth in engagement with the ratchet wheel. There is therefore no dragging of the tooth 37 over the teeth of the wheel and the wear of these parts is practically eliminated.

For the purpose of operating the cross feed manually a handle 50 is mounted upon a two-armed lever 51 loosely pivoted upon the stud 23. At its opposite end the lever 51 is provided with a pinion 52 which may be moved into or out of engagement with the ratchet wheel 22 and which may be angularly adjusted with reference to the lever 51. The details of this mechanism are more clearly shown in Fig. 12 of the patent to Norton, No. 672,838 to which reference is made for a full description thereof. The lever 51 is also provided with a shield 53 projecting laterally from the end of the lever and covering a portion of the teeth of the ratchet wheel 22. This shield acts to limit the automatic cross feed of the grinding wheel, the feed continuing until the shield 53 is moved around into a position in which it prevents the engagement of the feed pawl tooth 37 with the teeth of the ratchet wheel 22.

It is sometimes desirable to provide a positive stop for the cross feed when the same is being manually operated. For this purpose we have provided a projecting portion or stop 54 upon the end of the lever 51. At its left hand end this stop is provided with a substantially radial shoulder 55 having a stud 56 projecting therefrom, while the opposite end of the stop is rounded off to form a cam surface 57.

When the stop is to be used the sleeve 16 is adjusted on the arm 15 until its pivoted connection to the rack 17 is axially aligned with the stud 14. The engagement of the shoulder 55 with the square end of the feed pawl 34 then positively prevents further movement of the lever 51. The stud

56 at the same time enters a recess 58 in the end of the feed pawl and thus prevents the pawl from moving out of engagement with the stop 54.

5 If the ratchet wheel 22 is rotated manually in the opposite direction to withdraw the wheel from the work the curved cam surface 57 will engage the pawl 34 and the tooth 37 and move them away from the wheel, thus permitting the stop 54 to pass freely thereunder.

It is sometimes desirable to cut out entirely the automatic cross feeding feature of the machine, which result is very simply attained in our construction by swinging the feed pawl 34 manually backward to the position indicated in dotted lines at 34^a in Fig. 3. The plunger 39 then engages the left hand side of the cam 38 thus holding 20 the feed pawl in the dotted line position.

Having thus described our invention it will be evident that changes and modifications can be made therein without departing from the spirit and scope thereof as set 25 forth in the claims and we do not wish to be limited to the details herein disclosed, but

What we do claim is:

1. In a grinding machine, a feeding device comprising a ratchet wheel, an arm pivoted 30 concentrically therewith, a feed pawl pivoted to said arm, and means to cause the ratchet-engaging portion of said pawl to move in a closed path, with said pawl in engagement with said wheel during its operative move- 35 ment only.

2. In a grinding machine, a feeding device comprising a ratchet wheel, an arm pivoted concentric therewith, a feed pawl pivoted to said arm, and means to cause the 40 ratchet-engaging portion of said pawl to engage and feed said ratchet wheel, to thereafter move said pawl away from said wheel, and to return said pawl to initial position while out of contact with said wheel.

45 3. In a grinding machine, a feeding device comprising a ratchet wheel, an arm pivoted concentric therewith, a feed pawl pivoted to said arm, and means for actuating said pawl, said arm being restrained from 50 free movement by a friction binder and said pawl having a limited free movement on said arm.

4. In a grinding machine, a feeding device comprising a ratchet wheel, an arm pivoted concentric therewith, a feed pawl pivoted to said arm, and means for actuating 55

said pawl, said arm being restrained from free movement by a friction binder and said pawl having a limited free movement on said arm and being further movable 60 manually to a wholly inoperative position.

5. In a grinding machine, a feeding device comprising a ratchet wheel, an arm pivoted concentric therewith, a feed pawl pivoted to said arm, and means for actuating 65 said pawl, said arm being restrained from free movement by a friction binder and said pawl carrying a yielding plunger effective to engage a fixed cam stop to limit the free movement of said pawl, said plunger 70 being manually movable beyond said stop and thereafter engaging the opposite side of said stop to retain said pawl in a wholly inoperative position.

6. In a grinding machine, in combination, 75 a ratchet wheel, a feed pawl operable to rotate said wheel, a manually operable lever, and means to adjustably secure said lever to said wheel, said lever and pawl having engaging portions effective to positively 80 limit movement of said lever toward said pawl in one direction, while permitting free relative movement of said lever in the opposite direction.

7. In a grinding machine, in combination, 85 a ratchet wheel, a feed pawl operable to rotate said wheel, a manually operable lever, and means to adjustably secure said lever to said wheel, said lever and pawl having engaging portions effective to positively 90 limit movement of said lever toward said pawl in one direction, said engaging portions comprising abutting shoulders on said lever and pawl, and a stud on one part en- 95 gaging a recess in the other part and limiting the outward movement of said pawl away from said ratchet wheel.

8. In a grinding machine, a feeding device comprising a ratchet wheel, a feed pawl for said wheel, means to give said pawl an 100 operative movement in engagement with said wheel, and means to move said pawl out of engagement with said wheel at the beginning of the idle return stroke and to hold said pawl out of engagement with said 105 wheel until the pawl is positioned to begin its next operative stroke.

In testimony whereof we have hereunto set our hands.

JOSEPH S. WILCOX, JR.
ALBERT TURNER.
HOWARD W. DUNBAR.
